UNITED STATES PATENT OFFICE.

FREDERICK EDWARD HODDERSEN-BALLING, OF BROOKLYN, NEW YORK.

HAM BOILER.

Application filed April 23, 1925. Serial No. 25,250.

To all whom it may concern:

Be it known that I, FREDERICK EDWARD HODDERSEN-BALLING, a citizen of the United States, residing at Brooklyn, in the county 5 of Kings and State of New York, have invented certain new and useful Improvements in Ham Boilers, of which the following is a specification.

This invention relates to ham boilers, an 10 object of the invention being to provide an improved ham boiler so constructed that the waste at the knuckle end of the ham is reduced to a minimum while the ham is so shaped as to insure the proper slicing there- 15 of, and which boiler will be simple in construction and operation. A further object 20 of the invention is the provision of an improved boiler in which the cover can be readily and quickly attached and detached by a simple improved locking means efficient 25 to maintain the cover in place during pressing and cooking of the ham and the manipulation of the boiler by the operator.

In the drawings accompanying and forming 30 a part of this specification, Fig. 1 is a longitudinal sectional view of this improved ham boiler; Fig. 2 is a top view thereof with the cover in place; Fig. 3 is a cross sectional view taken on line 3—3 of Fig. 2, looking in the direction of the arrows; Fig. 4 is a detail view of one 35 end of the body of the boiler; Fig. 5 is a top view of the cover with the handle bar removed; Fig. 6 is a detail partly sectional view of the latch member and its cooper- 40 ating latch at one end of the body, and Fig. 7 is a detail perspective view of the swinging latch member.

Similar characters of reference indicate 45 corresponding parts in the several views. Before explaining in detail the present improvement and mode of operation thereof, I desire to have it understood that the invention is not limited to the details of 50 construction and arrangement of parts which are illustrated in the accompanying drawings, since the invention is capable of other embodiments, and that the phraseology which I employ is for the purpose of description and not of limitation.

This improved ham boiler comprises a body 2 of oval form having a bottom 3 pro- 55 vided with an inclined portion or end 4, which bottom is connected with the side

walls 5 by a sloping wall 6, thus avoiding sharp corners difficult to clean and keep in a sanitary condition. It also saves metal and reduces the weight of the boiler. The inclined bottom portion is provided with a keel 7 which enables the boiler to rest firmly 60 upon any suitable support without tipping forward. The cover 8 of suitable form to fit into the body comprises a flat plate, which by reason of the construction herein- 65 after described, may have but a very short depending flange 9 or no flange at all, since the stiffening or reinforcing means, about to be described, will sufficiently reinforce the cover so that this flange may be made as short as possible.

Extending lengthwise of the cover midway of its width is a reinforcing rib 10 having near each end a pair of cross reinforcing bars or members 11 rib-connected with the longitudinally extending rib as at 12. This construction efficiently reinforces the cover, which together with the body, will be preferably made of aluminum, so that the necessity of having a long depending flange on the cover is avoided.

The handle bar 13, which serves not only as a means for manipulating the boiler, but also for locking the cover to the body comprises a lengthwise extending bar provided along its underside with a reinforcing rib 85 14 and for a part of its top side with a similar reinforcing rib 15. This handle bar is provided with a pair of recessed and elongated slots 16 for the reception of headed bolts 17 projecting into the rib of the cover 90 adjacent to the cross ribs thereof.

The longitudinally extending rib on the cover together with that on the handle bar serves to limit the downward movement of the handle bar and thus prevent the heads of 95 the bolts from projecting beyond the top of the handle bar and catching in the top side edges of the slots. The elongated character of the slots enables one end of the handle bar to be pressed further down than the other and the bar to have a somewhat longitudinal movement relatively to the cover, which enables the locking hooks, hereinafter referred to, to be self-adjusting and a firmer engagement thereof with the body ratchet 100 maintained.

The handle bar is provided with a pair of rib reinforced cross bars 18, the ends of

which terminate in tubular sockets 19 for the reception of coil springs 19' the lower ends of which receive studs 20 carried at the ends of the cross ribs of the cover. Thus 5 the handle bar is connected to the cover midway of the length thereof by a pair of headed bolts and also has a resilient four point connection with the cover whereby a better and more equal compression and 10 shaping of the ham is obtained when it is placed in the boiler and also a better and more equal shaping thereof obtained during the cooking of the ham. The handle bar is provided at each end with a swinging member 15 or latch lever 21, as it is herein called, each provided with a pair of transversely extending teeth or hooks, one as 22 located horizontally of the latch member at its lower end and the other 23 extending vertically 20 along one edge of the latch lever. The horizontally located teeth are crosswise inclined, the inclination of the teeth of one latch member being opposite to that of the other and both teeth are beveled inward 25 toward the lever.

Carried at each end of the body for cooperating with the latch lever is a set of ratchet teeth 24 likewise crosswise inclined, those at one end of the body being inclined 30 opposite to those at the other end of the body and these ratchet teeth along one edge are cut or beveled inwardly to form a set of cooperating vertical teeth 25 for the vertically located tooth or hook 23 of its ratchet 35 lever. The vertically located tooth of one latch member is on the opposite side from that of the other latch member. Thus the handle bar and thereby the cover is connected at each end of the boiler by a double 40 locking means which enables the boiler to be readily manipulated without liability of the cover becoming separated from the body, either during the handling or cooking of the ham, since the inclination of the horizontally 45 extending ratchet teeth tends to pull the vertically extending ratchet teeth into engagement when the boiler is lifted by the handle bar and thus maintain the cover locked to the body against premature displacement during the handling or cooking 50 of the ham in the boiler.

Furthermore, the vertically located locking means also acts to maintain the crosswise or horizontally extending locking means 55 in engagement with each other during the pressing of the ham in the boiler prior to its cooking, and during the shrinkage of the meat while being cooked.

From the foregoing, it will be seen that 60 I have provided a very much improved ham boiler in which proper and adequate pressure can be brought upon the ham during the pressing of the ham into the boiler and effectively maintained thereon during the 65 cooking process so that the ham will be

properly shaped and in which the front end of the boiler will more nearly conform to the knuckle end of the ham and leave but little space for the forcing of the fat into this part of the boiler and the consequent 70 waste thereof around the knuckle end of the ham. At the same time the handle bar which serves as a means for connecting the body to the cover and also as a means for manipulating the boiler is 75 efficiently locked to the body by a double form of locking means which, during manipulation of the boiler by the operator tends to increase its holding efficiency rather than diminish it. In other words, 80 the crosswise inclination of the horizontal locking teeth during the lifting of the boiler tends to maintain the vertically located locking teeth in proper engagement while at the same time these vertically extending locking teeth tend to hold the horizontal locking teeth of the latch levers in proper 85 cooperating position to engage successive teeth during the compression of the ham by means of the cover so that each not only 90 performs its own function, but also assists the other in performing its function.

It is to be understood that by describing in detail herein any particular form, structure or arrangement, it is not intended to limit the invention beyond the terms of the several claims or the requirements of the prior art.

Having thus explained the nature of my 100 said invention and described a way of constructing and using the same, although without attempting to set forth all of the forms in which it may be made, or all of the modes of its use, I claim:

1. In a ham boiler comprising a body 105 and a cover, a locking means for connecting the cover with the body and comprising a swinging member connected with the cover and cooperating means carried by said swinging member and body and inclined crosswise in the direction of the width of the body.

2. In a ham boiler comprising a body and a cover, a locking means for connecting the cover with the body and comprising a 115 swinging member connected with the cover and cooperating means carried by said swinging member and body and inclined crosswise in the direction of the width of the body and comprising a series of ratchet teeth and a cooperating tooth.

3. In a ham boiler comprising a body and a cover, a locking means for connecting the cover with the body and comprising a 125 swinging member connected with the cover and cooperating means carried by said swinging member and body and including cooperating vertically disposed teeth carried by said body and swinging member.

4. In a ham boiler comprising a body

and a cover, a locking means connecting the cover with the body and comprising a swinging member connected with the cover and cooperating vertically disposed and horizontally disposed ratchet teeth carried by said body and swinging member.

5. In a ham boiler comprising a body and a cover, a locking means connecting the cover with the body and comprising a 10 swinging member connected with the cover and cooperating vertically disposed and horizontally disposed ratchet teeth carried by said body and swinging member, the horizontally disposed teeth being crosswise 15 inclined in the direction of the width of the body.

6. In a ham boiler comprising a body and a cover, a locking means connecting the cover with the body and comprising a 20 swinging member connected with the cover and cooperating vertically disposed and horizontally disposed ratchet teeth carried by said body and swinging member, the vertically disposed teeth of one part being 25 formed by the ends of the horizontally disposed teeth.

7. In a ham boiler comprising a body and a cover, a locking means for connecting the cover with the body and comprising a 30 swinging member connected with the cover and having a pair of transversely disposed inwardly projecting teeth and cooperating teeth carried by the body.

8. In a ham boiler comprising a body and a cover, a locking means for connecting the cover with the body and comprising a 35 swinging member connected with the cover and having a pair of transversely disposed inwardly projecting teeth and cooperating teeth carried by the body, some of said 40 cooperating teeth being crosswise inclined in the direction of the width of the body.

9. In a ham boiler comprising a body and a cover, a locking means for connecting the cover with the body and comprising a 45 swinging member connected to each end of the cover, and cooperating means carried by said swinging member and body and inclined crosswise in the direction of the width 50 of the body, the inclination thereof at one end of the body being opposite to that at the other end.

10. In a ham boiler comprising a body and a cover, a locking means for connecting the cover with the body and comprising a 55 swinging member connected to each end of the cover and having a pair of transversely disposed inwardly projecting teeth, a tooth of one swinging member being oppositely disposed to a similar tooth of the other swinging member, and cooperating teeth carried by the body.

11. In a ham boiler comprising a body and a cover, a locking means for connecting 60 the cover with the body and comprising a

swinging member connected with the cover, said swinging member and body having one transversely disposed teeth projecting in the same direction and the other teeth cooperating therewith.

70

12. In a ham boiler comprising a body and a cover, a locking means for connecting the cover with the body and comprising a swinging member connected with the cover, said swinging member and body having one 75 transversely disposed teeth projecting in the same direction and the other teeth cooperating therewith, one of said transversely disposed teeth and its cooperating teeth being inclined crosswise in the direction of the 80 width of the body.

13. In a ham boiler comprising a body and a cover, a locking means for connecting the cover with the body and comprising a 85 swinging member connected with the cover, and cooperating means carried by said swinging member and body and comprising transversely disposed teeth carried by the swinging member and projecting in the same 90 direction, and teeth carried by the body having additional teeth formed at the ends thereof.

14. In a ham boiler comprising a body and a cover, a locking means for connecting the cover with the body and comprising a 95 swinging member connected with the cover, and cooperating means carried by said swinging member, and body and comprising transversely disposed teeth carried by the swinging member and projecting in the same 100 direction, and teeth carried by the body having additional teeth formed at the ends thereof, some of said teeth being inclined crosswise in the direction of the width of the body.

105

15. In a ham boiler comprising a body and a cover, a locking means for connecting the cover with the body and comprising a swinging member connected to each end of the cover, and cooperating means carried by each swinging member and body and comprising inwardly projecting transversely disposed teeth, and teeth carried by the body having additional teeth formed at the ends thereof, some of said teeth being inclined 110 crosswise in the direction of the body, the teeth at one end of the body being inclined in a direction opposite to those at the other end thereof.

115

16. A ham boiler comprising a body, a cover, a handle bar spring-connected with the cover, said bar having elongated and recessed slots and headed means located in said slots for connecting the handle bar with the cover.

125

17. A ham boiler comprising an oval shaped body having an inclined bottom end, a cover therefor, a handle bar, said cover and handle bar each having lengthwise extending reinforcing ribs, each having cross 130

- extending members, resilient means between the cross extending members of the handle bar and cover, headed bolts connecting the handle bar with the rib of the cover, said handle bar having elongated and recessed slots for the reception of said bolts, swinging latches at the ends of the handle bar and locking means between the latches and the body at each end thereof. 25
18. A ham boiler comprising an oval shaped body having an inclined bottom end, a cover therefor, a handle bar, said cover and handle bar each having lengthwise extending reinforcing ribs, each having cross extending members, resilient means between the cross extending members of the handle bar and cover, headed bolts connecting the handle bar with the rib of the cover, said handle bar having elongated and recessed slots for the reception of said bolts, swinging latches at the ends of the handle bar and locking means between the latches and the body at each end thereof, said locking means including two transversely extending ratchet teeth on each latch. 30
19. A ham boiler comprising an oval shaped body having an inclined bottom end, a cover therefor, a handle bar, said cover and handle bar each having lengthwise extending reinforcing ribs, each having cross extending members, resilient means between the cross extending members of the handle bar and cover, headed bolts connecting the handle bar with the rib of the cover, said handle bar having elongated and recessed slots for the reception of said bolts, swinging latches at the ends of the handle bar and locking means between the latches and the body at each end thereof, said locking means including two transversely extending ratchet teeth on each latch, one of which is inclined crosswise thereof. 35
- 20 slots for the reception of said bolts, swinging latches at the ends of the handle bar and locking means between the latches and the body at each end thereof, said locking

Signed at Brooklyn, New York, this 18 day of April, 1925.

FREDERICK EDWARD HODDERSEN-BALLING.
